ATTORNEY

UNITED STATES PATENT OFFICE.

ROBERT L. BEE, OF BINGHAM CANYON, UTAH.

TIE RACK.

Application filed September 14, 1928. Serial No. 305,995.

This invention relates to tie racks.

An object of the invention is the provision of a tie rack including a horizontal bar which is provided with a plurality of pointed elements to engage the tie and prevent slippage of the ties from the supporting bar.

Another object of the invention is the provision of a tie rack having a horizontally disposed bar, a vertically disposed bracket, and connecting means between the bracket and bar, said bar connecting means and brackets being formed of a single strip of metal.

A further object of the invention is the provision of a tie rack formed of a single strip of metal and which includes a horizontally disposed tie supporting member having a plurality of pointed elements to prevent slippage of the ties, a horizontally disposed connecting member for the tie supporting means, and a bracket, said bracket being adapted to provide means for securing and supporting the tie supporting means in spaced relation with a fixed support.

This invention will be best understood from a consideration of the following detailed description in connection with the accompanying drawings; nevertheless, it is to be understood that the invention is not confined to the disclosure being susceptible of such changes and modifications as shall define no material departure from the salient features of the invention as expressed in the appended claim.

In the drawings:

Figure 1 is a view in perspective of a preferred form of my invention,

Figure 2 is a plan view of the same;

Figure 3 is a vertical section taken along the line 3-3 of Fig. 2,

Figure 4 is a view in perspective of a modified form of the invention,

Figure 5 is a transverse vertical section of the tie rack shown in Fig. 4.

Referring more particularly to Figs. 1 to 3 inclusive, a tie rack is illustrated formed of a single strip of metal which is bent intermediate its ends to form a U-shaped bracket generally designated by the numeral 10. This bracket includes a bridging portion 11 and inturned side portions 12. The inturned legs 12 are bent inwardly as shown at 13 and at right angles to the plane of the bracket 10. The remaining portions of the strip of metal between the end and the portion 13 are bent at right angles to the portion 13 and in opposite directions to provide tie supporting

bars 14. These bars lie in the same plane with the portion 13 and are connected to the bracket 10 by means of the portion 13.

Pointed elements 15 project in a vertical plane from the upper surface of the bar 14 and are adapted to engage the tie in a penetrating manner to maintain the ties against slippage from the bars 14. In order to support the pins 15 in the bars 14, said bars are provided with a plurality of spaced passages in which the inner end of the pins are forced and in this case the diameters of the passages are slightly less than the diameters of the pins.

The pins may be held in position in the passages in the bars 14 by providing passages in the bars of the same diameter as the diameter of the pins. Portions of the bars at a point where the pins have entered the passages may be compressed for clamping the pins to the bars.

A spring retaining member 20 engages a notch 21 in the bridging portion 11 and is secured in an ornamental member 22 which may assume the shape of the head of an animal. The head in this case is formed of clay or plaster of Paris and the spring member 20 being rigid with the head will retain the rear portion of the head in flat engagement with the bracket 10.

A modified form is shown in Fig. 4, and is formed of a flat strip of metal instead of the cylindrical strip of metal shown in Figs. 1 to 3, inclusive. In this instance one end of the flat strip of metal is rolled to form a tubular member 30 which has its free end, as shown at 31, disposed between the flanged portions 32. The intermediate portion 33 of the flange 32 is located in a vertical plane as are the teeth 34. Said teeth are adapted to engage the material of the ties and prevent slippage of the same from the cylindrical bar 30.

Projecting laterally and at right angles to the intermediate portion 33 of the flange is a section 40 having depending reinforcing flanges 41. Each flange 41 has a right angular extension 42 and which in turn is provided with an integrally formed parallel portion 43 acting as a reinforcing member for the extension 42. A bracket in the form of a plate 50 extends upwardly from the member 40 and has reinforcing inturned flanges 51. A lip 52 projects inwardly and upwardly from the upper end of the flange of the plate 50 and is adapted to be inserted

in an opening in the head, for maintaining the head in position on the bracket plate 50. The bracket plate 50 is provided with a perforation 53 adapted to receive a screw or tack 5 for securing said bracket plate to a fixed support, while the bracket 10 is provided with passages 54 through which are inserted nails 55 for securing said bracket to a fixed support.

10 I claim:

A tie rack comprising a bracket formed from the bent intermediate portion of a metal

strip, portions of the strip between the ends of the bracket being bent at right angles to the plane of the bracket, the remaining portions of the strip towards the end thereof being bent opposite to each other and at right angles to the last mentioned bent portions of the legs to provide tie supporting bars, said bars being provided with pointed elements 15 adapted to coact with the ties to prevent slip-
page of said ties from the bars. 20

ROBERT L. BEE.
